COMBINATION GLASS, CIGARETTE, AND ASH RECEIVER

Max Schulz, Oakland, Calif., assignor to Frederick
E. Anderson, Burlingame, Calif.

Application April 26, 1949, Serial No. 2,278

Term of patent 14 years

(Cl. D85—2)

To all whom it may concern:

Be it known that I, Max Schulz, a citizen of the United States of America and resident of Oakland, county of Alameda, State of California, have invented a new, original, and ornamental Design for a Combination Glass, Cigarette, and Ash Receiver, of which the following is a specification, reference being had to the accompanying drawings, forming part thereof.

Referring to the drawings:

Fig. 1 is a perspective view of a combination glass, cigarette, and ash receiver showing my new design.

Fig. 2 is a side elevational view thereof taken from the right of Fig. 1.

I claim:

The ornamental design for a combination glass, cigarette, and ash receiver, substantially as shown.

MAX SCHULZ.
